United States Patent Office.

EDWARD S. COLTON, OF BOSTON, MASSACHUSETTS, ASSIGNOR TO THE
COLTON REFRIGERATOR COMPANY, OF SAME PLACE.

Letters Patent No. 101,588, dated April 5, 1870.

IMPROVED REFRIGERATOR.

The Schedule referred to in these Letters Patent and making part of the same

To all whom it may concern:

Be it known that I, EDWARD S. COLTON, of Boston, in the county of Suffolk and State of Massachusetts, have invented an Improved Refrigerator; and I do hereby declare that the following is a full, clear, and exact description of the construction and operation of the same, reference being had to the accompanying drawings and letters of reference marked thereon, in which—

Figure 1 is a sectional elevation of my invention.

Figure 2, a plan view of the ice-receptacle and roof.

This invention is an improvement on my patent No. 69,971, dated October 22, 1867, and consists of certain details of construction, which will be more fully described hereinafter.

I construct my refrigerator in the following manner and of the following materials:

The outer casing A is composed of boards of about three-fourths of an inch in thickness, within which is a similar casing, B, of half-inch boards.

Between the casings A and B is a space of two inches, which is filled with felt or other like material, C.

D represents a third casing of boards within the casing B, which constitutes the refrigerating-chamber D'.

Into the space between the casings B and D, which is about two inches wide, is introduced a sheet-metal water-tank, E.

F represents the roof or cover of the chamber D', which rests upon the upper edge of the casing D, its edges projecting over the tank E.

The cover F is made of the hip-roof form, as shown in fig. 2, and is provided with a box or ice-receptacle, G, on its upper side, which box may be secured there-

to or otherwise, an outlet for the water which accumulates therein being provided.

F' is a gutter for carrying off the condensed moisture which accumulates on the lower side of the roof F.

The receptacle G is filled with a mixture of ice and salt, or ice alone, if preferred, and, by reason of its peculiar form, radiates, as it were, the intense cold caused by the melting of the ice into the chamber D'; meanwhile the water, which falls from the projecting eaves of the roof F, keeps the contents of the tank E at a low temperature, while the metal of the tank is protected from injurious effects from condensed moisture, and the atmosphere of the chamber is kept dry by means of the wooden casing D, thus enabling the water to be utilized for cooling-purposes, without imparting moisture to the air or injuring the walls of the tank.

The tank E extends around three sides of the refrigerator, the remaining side, as well as the top and bottom, being composed of wood and felt.

Having thus fully described my invention,

What I claim as new, and desire to secure by Letters Patent, is—

The wooden casings A, B, and D, provided with non-conducting space C and water-space E, ice-holder G, hip-roof F, gutter F', and provision-chamber D', all constructed and arranged as herein described, for the purposes specified.

In testimony whereof I have signed my name to this specification in the presence of two subscribing witnesses.

EDWARD S. COLTON.
